18 INVENTOR
CHARLES ALLEN.
BY Chas. E. Townsend

ATTORNEY

UNITED STATES PATENT OFFICE.

CHARLES ALLEN, OF EL PASO, TEXAS.

LAUNDER.

Application filed June 29, 1921. Serial No. 481,308.

To all whom it may concern:

Be it known that I, CHARLES ALLEN, a citizen of the United States, residing at El Paso, in the county of El Paso and State of 5 Texas, have invented new and useful Improvements in Launderers, of which the following is a specification.

This invention relates to a launder device for conveying dewatered or partially dewatered ores, sands, and the like, and has for its object to divert a stream whenever it exceeds a certain predetermined degree of dilution.

In certain types of classifiers, the water 15 entering the receptacle with the feed stream, in excess of that discharged with the classified or dewatered material, overflows the top of the receptacle. The device functions satisfactorily only as long as the solids settling 20 in the receptacle are in quantity just sufficient to supply the outflow through the orifice provided for their discharge, after a bed of solids have settled in the receptacle. If the solids settle in excess of the discharging 25 capacity of the orifice the receptacle fills with settled solids when particles that should be discharged through the orifice pass away with the overflow, and if less solids settle in the receptacle than are dis- 30 charging through the orifice, as soon as the settled solids over the orifice are discharged, a flood of practically the unclassified feed stream is discharged through the orifice, the volume so discharged being several times 35 that of the settled sand previously discharged in the same period of time.

When a body of settled sand overlies an orifice the friction of the particles among themselves is such that the sand outflows 40 through the orifice with very much less velocity than the velocity of issuance of a liquid under the same velocity head. In tests made with a receptacle approximating four feet in depth from orifice to overflow 45 lip, the orifice being one inch in diameter, the settled solids discharged through the orifice with a velocity of approximately twenty inches per second, whereas, under a like velocity head water will issue with a 50 theoretical velocity of approximately two hundred inches per second. Hence the water discharge would be ten times the volume of the sand.

In the wet milling of ores, washing of 55 sand and the like both the relative propor-

tion of water to solids and the relative proportion of the different mesh size particles to each other vary largely. Among the causes for these variations is the mechanical condition of the solids fed to the pulverizing 60 machine. It is sometimes nearly all coarse material which is pulverized comparatively slowly, at other times there is a large percentage of fine and very fine material which passes through the pulverizer much more 65 rapidly. Such variation in the character of the solids fed is practically unavoidable for segregation takes place in the bins from which the head is drawn.

The total quantity of solids in the pul- 70 verizer discharge may remain normal and there be great percentage differences from the normal in the relative mesh size of the particles. In a cone classifier of the type with which the present invention is concerned, 75 every such variation increases or diminishes the quantity of solids that should pass to the bottom discharge orifice.

The foregoing are some of the principal 80 reasons why classifiers and dewaterers of the type shown will with more or less frequency discharge the practically unchanged feed stream. The damage of such erratic discharge is far-reaching in practice for it is not a question of simply stopping the flow 85 and then immediately resuming normal operations. In many cases it means hours of sub-normal operation.

For example: where a cone classifier is used in closed circuit with a ball mill, it 90 will be evident that if no provision were made to prevent it, when the classifier "breaks loose" (as previously described) and discharges a large volume of the unclassified feed stream, the whole of the dilute 95 stream would pass into the ball mill. It is seldom that a ball or tube mill will pulverize with high efficiency when the feed stream to it contains more than 40% water (40% water and 60% solids). The dilute discharge 100 from the classifier would almost empty the ball mill of solids and normal operation cannot be resumed by simply resuming the normal feed. It is practically a case of re-commencing the pulverizing operation with 105 the mill, and it usually takes about eight hours from the turning in of the feed to bring a ball mill to its normal pulverizing capacity.

Should the material be fed direct to grav- 110

ity concentrators, flotation cells, or the like, then when the classifier "breaks loose" the flood of water would put them out of commission, causing losses of both values and time.

When a dewatering device is used to build stock piles or to fill bins, then when the material "breaks loose" the discharge not only adds water to the previously dewatered material but also contaminates the material in the pile, or the bin by adding to it the material discharged with the water.

In and by the present invention I provide a launder device whereby material of a certain dilution will fall through a gap in the bottom of the launder, and whenever the material reaches a predetermined degree of dilution it will pass the gap and be diverted elsewhere.

20 In the accompanying drawings—

Fig. 1, shows a classifier arranged in closed circuit with a ball mill and having a launder device interposed between the classifier and ball mill, such launder device being provided with a gap in accordance with my invention.

Fig. 2, shows a modified form of the gap of the launder.

Fig. 3, shows a further modification of the gap of the launder wherein provision is made for adjusting the width of the gap.

Fig. 4, shows a still further modification of the same wherein the gap of the launder is provided with a false bottom, the angle of which may be adjusted.

Referring in detail to the accompanying drawings, I show a cone classifier 10 having an overflow rim at 11, emptying into a discharge launder 12. The classifier has a discharge orifice 13 at its apex for supplying classified material to any desired point or receptacle, such as a ball mill 14. A feed stream is supplied to the classifier through the launder 15.

45 Instead of directly discharging the classified material into the ball mill, I interpose a special form of launder 16, having an upper part 17 and a lower part 18 with an intermediate gap 19. The upper part 17 has a declination of between two and three inches to a foot of length for purposes hereinafter to be made clear. The gap 19 communicates with the trough 20 which empties into the ball mill or other receptacle.

55 In Fig. 2, I show a modification of the launder 16, wherein the upper part 17 is provided, at its lower end, with an upturned portion 21. In Fig. 3, I show a plate 22 slidably mounted on the launder 16 for the purpose of adjusting the width of the gap 19. In Fig. 4, I show a false bottom 23 held in place on the upper portion 17 by means of a screw 24, or otherwise, and provide means, such as a wedge 25 for adjusting the 60 inclination of the false bottom 24.

Settled quartz sand in water discharged through an orifice in the bottom of a receptacle in which a bed of settled sand is maintained over the orifice, is discharged through the orifice accompanied by approximately 70 30% water (30% water and 70% sand by weight). Such material will seldom flow down a launder having a fall of two inches per foot of length, and will usually flow down a launder having a fall of three 75 inches per foot, whereas, if the same sand be diluted to several parts of water to one of sand it will flow down the same launder with a high velocity, and on this fact is based the functioning of the "launder gap." 80

Referring to Fig. 1—when a normal discharge is issuing from 13 (approximately 70% solids and 30% water) the discharge flows slowly down the inclined plane formed by the launder part 17, and falls off the 85 upper edge of the gap into the trough 20, down which it flows to the ball mill. Due to the inclination of part 16, the velocity of the flow is such that it cannot jump the gap 19 and flow down the part 18. Assume now that the sand settling in 10 has so diminished that the cone is emptied of its normal bed of settled solids over the orifice 13. The latter will then discharge a 90 large volume of the practically unclassified feed stream. As hereinbefore stated the volume discharged under these conditions will approximate ten times that of the discharge when the classifier is functioning normally, and the increase is almost wholly water. A 95 stream of this composition and volume will flow down a launder having a fall of from two to three inches to the foot with a very high velocity and a very large portion of the stream will jump the gap in the bottom 100 of the launder. With a "step down" as shown by Fig. 1, or an upward inclination to the bottom of the launder above the gap as shown by Fig. 2, or with the false bottom of Fig. 4, the entire stream may be 110 caused to pass over the gap.

Anything that increases the velocity of the flow down the launder above the gap 19 increases the tendency of the stream to jump the gap, and an increase in either the volume 115 or the dilution, or both, increases the velocity and both are effective on the velocity the instant that the last of the sand bed normally maintained in the classifier is discharged through the orifice.

Having thus described my invention, what I claim and desire to secure by Letters Patent is:

1. The method of conducting material in a dewatered or partially dewatered state to 12 a place of use so as to divert substantially all the material when it exceeds the desired degree of dilution which consists of flowing the material down an inclined launder having a gap in its bottom through which the 13

material is discharged when it is of a predetermined degree of dilution, and arranging the launder at such an inclination and proportioning the size of the gap as to cause the material to jump the gap when it exceeds the predetermined degree of dilution.

2. The combination with a feeder for discharging material in a dewatered or partially dewatered state, of an inclined launder

10 to receive the discharged material, said launder having a gap in its bottom through which the material passes when it is of a predetermined degree of dilution, a branch launder communicating with said gap to 15 conduct the material to the place of use, said first mentioned launder being at such an inclination and the size of the gap being of such width as to cause substantially all the

material to jump the gap when it exceeds the predetermined degree of dilution.

3. The combination set forth in claim 2 including means for varying the relation between the inclination of the launder and the size of the gap whereby to permit material of varying degree of dilution to pass 25 through the gap and enter the branch launder.

4. The combination with a receptacle for discharging dewatered or partially de-watered ores, sand and the like, of means to 30 direct the discharged material to a place of use and means automatically responsive to changes in the fluidity of the stream to divert the same when it falls below a predetermined degree of dilution.

CHARLES ALLEN.
